UNITED STATES PATENT OFFICE.

ALFRED E. JURY, OF RUTHERFORD, NEW JERSEY, ASSIGNOR TO THE HARTFORD RUBBER WORKS COMPANY, OF HARTFORD, CONNECTICUT, A CORPORATION OF CONNECTICUT.

WEFTLESS FABRIC AND METHOD OF MANUFACTURING SAME.

Application filed November 23, 1923. Serial No. 676,496.

This invention relates to new and useful rubberized fabric, particularly suitable for the manufacture of tires, and to methods of manufacturing the same.

5 It has been found desirable for some purposes to employ a plurality of plies of cords in parallel relation in each and all of the plies. This invention, for one object, contemplates an improved material meeting this 10 need and a simple process for obtaining the same.

Another object of the invention is to provide a cord material having improved resistance to tearing and valuable for many 15 purposes, particularly in connection with the manufacture of tires as a means for preventing or limiting the extent of a blow-out. Still another object of the invention is to provide a new and improved process 20 for obtaining sheet material more resistant to tearing and which may be made rapidly and economically. These are some of the objects of the invention, others will appear in the detailed disclosure following.

25 With the illustrated embodiments in mind and without intention to limit the scope more than is required by the prior art, the invention consists in latex treating and drying a multiplicity of cord-elements in such 30 a way as to obtain in one operation a multiply weftless fabric, that is, a fabric consisting of superimposed as well as side-by-side disposed cord-elements in close-lying parallel relation united by rubber. It also contemplates grouping a number of parallel 35 cords and uniting the groups of parallel cords with rubber composition, preferably by calendering.

40 Embodiments of the invention are illustrated in the accompanying drawings, in which:—

Figure 1 is a cross-section of typical weftless fabric consisting of a single layer of parallel cords;

45 Figure 2 is a cross-section of multi-ply weftless fabric.

Figures 3 and 4 are cross-sections of different forms of grouped cord weftless fabric, the former showing only one layer of cords 50 and the latter a plurality of layers of cords;

Figure 5 is a diagrammatic elevation of an apparatus suitable for treating cords with latex and drying the same;

Figures 6 and 7 are details of one of the

combs for controlling the spacing and the 55 relation of the cords;

And Figure 8 is a diagrammatic elevation of a calendar and appurtenances for separating latex treated and dried cords into groups and uniting the groups into a unitary flexible sheet material.

Referring to the drawings, cords 1, or other form of filamentary material, wound on spools, are arranged to be delivered from a creel 1'. The individual cords are threaded through eyes on the creel and eyes on a thread-board 2, from which they pass through power-driven tension rolls 3 and an expansion-comb 4 on their way to a tank 5 holding rubber latex or similar material. 70 The devices which act upon the cords prior to their entry into the latex in the tank 5 serve, preferably, to arrange the cords so that each one is parallel and touches cords on either side thereof and also superimposed 75 thereon if desired.

The cords pass from the expansion-comb 4 over an idler 6 mounted, as here shown, immediately above the entrance side of the tank 5. Mounted adjacent the bottom of 80 the tank is a pair of squeeze-rolls 7. Although squeeze-rolls are here shown, it will be understood that a single roll may be employed if desired. A latex tank 8 is arranged to deliver latex into the tank 5. 85 Mounted upon the tank 5 is an expansion-comb 9 above which is an idler 10 and in line with the comb and idlers is a double doctor-blade 11, adapted to scrape excess latex from the cords emerging from the tank. 90 A series of dry-cans 12 are here shown mounted above the tank and adapted to receive cords emerging therefrom. The dry-cans supported by standards 13 are internally heated, preferably by steam supplied through their axes. The cords meet, as 95 they pass from tank 5 to the first of the series of dry-cans, a thin liner sheet 14, which serves as a carrier or conveyor. This carrier-sheet prevents sticking of the cords to the dry-cans while in a wet or moist condition. The material passing from the dry-cans is conducted through idlers 15 and thence to a wind-up roll 16, which may be 100 driven in any convenient manner.

With the apparatus illustrated in Figure 5 of the drawings, weftless fabric may be manufactured in the form of a single layer

of cords, as shown in Figure 1, or of a plurality of layers of cords, as shown in Figure 2, in one operation, by suitably varying the number of cords that are threaded through each dent of combs, as illustrated, for instance, in Figures 6 and 7 of the drawings. The number of cords threaded through each dent of the comb will vary with the type of comb employed, the size of the cords, and 10 the number of layers of cord it is desired to obtain in the finished material.

In this manner, a multiply weftless fabric—consisting of approximately two or more times as many cords as can be arranged 15 parallel and contiguous in a single layer of the desired width—may be made continuously in one operation with all the cords united together by rubber derived from latex by drying in situ thereon so as to more or less 20 thoroughly impregnate each and every one of the cords and also to substantially fill the voids or channels between the cords. This material may be used advantageously in connection with the building of tires, hose, 25 belting, and a variety of other articles of manufacture. No more operations are required in manufacturing the multi-ply weftless fabric of a single layer of cords, and a unitary flexible sheet with each cord cushioned in rubber is produced.

To obtain a weftless fabric which is more 30 resistant to tearing than former types in which the cords are uniformly separated or 35 spaced apart—in contra-distinction to contiguous—it has been found advantageous to arrange the cords non-uniformly and in groups, as shown in Figures 3 and 4 of the drawings, for instance. For this purpose, 40 one or two sheets of weftless fabric consisting of a single layer of cords, or a single multi-ply weftless fabric consisting of more than one layer of parallel cords, may be conducted from previously prepared rolls 45 20 and 21, over a guide-roll 22 to slitting blades or fingers 23. Any suitable number 50 of these blades 23 may be employed, but preferably they are of a number and size to divide the cords into groups about as indicated at *a* and *b* in Figures 3 and 4 of the drawings. The groups of cords are conducted from the blades 23 over a pressing roll 24, preferably, but not necessarily, provided with grooves 25 at the proper intervals. 55 The pressing roll 24 is free to turn with the intermediate roll 26 of a calender having other co-operating rolls 27 and 28, supported and driven in any convenient and well-known manner. A bank of rubber, 60 maintained at 28°, may be continuously filmed by the calender, as indicated at 29, so as to be continuously brought in contact with the groups of cords *a* and *b* at a point opposite the pressing roll 24, and moved 65 around with the cords to the right 30 where,

under pressure, the rubber composition is powerfully forced upon and between the groups of cords. Simultaneously, or in a second pass through the calender, another coat of rubber may be applied to the other 70 side of the material. In Figures 3 and 4 of the drawings, the grouped cord material is shown in cross-section and diagrammatically on an enlarged scale as it would appear after being calendered upon both faces but, 75 of course, the rubber composition may be applied to only one face if desired.

While it is preferred to manufacture the material, consisting of contiguous or close-lying parallel cords arranged in groups and 80 having the groups separated from one another by a substantial web of rubber composition, from the single or multi-ply weftless fabric mentioned above, the invention is not limited in its broadest aspect to the 85 same as the cords may be latex treated and dried in any other suitable and convenient manner, for instance, entirely separated and disconnected from each other before bringing them into proximity in sheet formation. 90 Alternatively, also, the cord-elements in each group might be webbed together with latex—either a single or plurality of layers in thickness—omitting to thread them through certain of the dents of the comb 9, 95 Figure 5,—for instance, the first, sixth, eleventh, sixteenth, etc., dents—in order to obtain the groups separated. This might be done most conveniently by drying them on a liner in the proper spaced and separated 100 relation between groups, and then passing the cords still on the liner through a calender for uniting the groups of cords together with rubber composition. In this alternative procedure, while it is preferred to dry the cords on a liner, the latter might be dispensed with, in some instances at least, and the groups of cords alone conducted in spaced relation to a calender for 105 coating and bonding together with rubber 110 composition.

In the claims, the term "cord-elements" is used comprehensively to cover single or plied yarns, threads, cords, rovings, or any other arrangements of fibers affording a strain-resisting element. In the claims also, the term "latex" is used to comprehend a natural or modified form of latex, that is, whether the latex is as obtained naturally, or diluted, or concentrated, or altered, by the addition of compounding and/or vulcanizing ingredients. For most practical purposes, however, natural latex as obtained from the plantations with a low percentage of preservative will be found satisfactory. 115

Many changes and alterations may be made without departure from the principles underlying the invention and reference should therefore be made to the accompanying 120 claims for an understanding of its scope. 130

Having thus described my invention, what I claim and desire to protect by Letters Patent is:—

1. A rubberized fabric consisting of parallel groups of parallel cord-elements held together in sheet formation and in spaced relation solely by rubber composition. 5
2. A rubberized fabric consisting of groups of parallel cord-elements held together in sheet formation and in spaced relation solely by rubber composition, each group being parallel to its neighbors and comprising at least two layers of cord-elements. 10
3. A fabric for manufacturing rubber articles consisting of latex treated and dried cord-elements arranged parallel and in groups, the groups of cord-elements held in spaced parallel relation and in sheet formation by rubber composition. 15
4. That method of manufacturing a rubberized fabric for incorporation in rubber articles which consists in, latex treating and drying parallel cord-elements, superimposing the cord-elements in layers to make a multi-ply weftless fabric, separating the multi-ply weftless fabric at intervals to form distinct groups of bonded together cord-elements, and joining the groups of cord- 20
- elements with rubber composition to form a manipulatable sheet. 30
5. As an article of manufacture, weftless fabric consisting of a multiplicity of cord-elements in side-by-side and superimposed and close-lying parallel relation, said cord-elements being webbed together to form a flexible sheet by dried rubber. 35
6. As an article of manufacture, weftless fabric consisting of a multiplicity of cord-elements in side-by-side and superimposed and close-lying parallel relation, said cord-elements being webbed together to form a flexible sheet by rubber derived from rubber latex applied thereto and dried in situ. 40
7. The method of manufacturing a rubberized fabric for incorporation in rubber articles which consists in, latex treating and drying parallel cord-elements to form a weftless fabric, separating the fabric at intervals to form groups of bonded together cord-elements in spaced relation to each other and joining the spaced groups with rubber composition to form a sheet. 45

Signed at New York city, county of New York, and State of New York, this 21st 50 day of November, 1923.

ALFRED E. JURY.
